INVENTOR.
Henry Pegac
BY A.W. Freeman
ATTORNEY.

UNITED STATES PATENT OFFICE.

HENRY REZAC, OF SIOUX FALLS, SOUTH DAKOTA.

WALL DUCT.

Application filed May 27, 1927. Serial No. 194,735.

This invention relates to certain new and useful improvements in wall ducts, and the primary object thereof is to provide a duct of this type which is formed in sections each having an open front provided with a removable cover, the sections having novel connections therebetween and being formed to be embedded in a wall and with the cover flush with the finished face of the plaster, together with means for holding pipes within the duct, whereby in event of leakage of the pipes or for any other purpose, access thereto is desired, such access may be had without cutting and removing the plaster.

A further object of the invention is to provide a duct of this type which will act to confine any fluid which may leak from the pipes within the duct, thereby to prevent the leakage from wetting and marring the plaster.

The invention still further aims to provide novel means for holding the pipes.

In the drawings:—

Fig. 1 is a front elevation of the invention;

Fig. 2 is a side elevation;

Fig. 3 is a section on line 3—3 of Fig. 1;

Fig. 4 is a section on line 4—4 of Fig. 2;

Fig. 5 is a section on line 5—5 of Fig. 2, and

Fig. 6 is a top plan view of one of the sections.

In proceeding in accordance with the present invention, each section of the duct is formed to have a back 1 and sides 2, the front being open. Each side 2 is flanged outwardly at 3 to lie parallel to the back and the free edges of the flanges are turned outwardly at right angles at 4 to form side guides for a cover 5. Nuts 6 are soldered or otherwise rigidly secured to the rear faces of the flanges 3 and are engaged by screws 7 which pass through the cover and through the flanges 3, so that the cover may be removed as desired or found necessary. Each section is provided with clips 9' or 10' by means of which same may be secured to the studding or built into a brick wall, the clips 9' being employed in the position shown in Fig. 1 in securing the section to studding, while the clips 10' are employed in the position of Fig. 1 in building the sections into a wall. The backs and sides at the ends of the sections are provided with extensions, the extensions at one end of each section being offset outwardly to form tongues 8 while

the extensions at the opposite end of the section are bent upon themselves as indicated at 9 and then bent upwardly as indicated at 10 to form sockets to receive the tongues 8 of an adjacent section. In this manner, it will be seen that a simple slip joint connection is provided enabling the sections to be easily and quickly connected and disconnected.

For the purpose of not only holding the pipes in fixed position in the duct, but also for the purpose of strengthening and bracing the latter, transverse plates 20 are provided which have downwardly flanged backs 21 and ends 22 which flanges abut the backs and sides respectively of the sections. The plates 20 are formed with U-shaped seats 23 which extend through the front sides of the plates and which are formed of various sizes to receive different sized pipes. Angle bars or strips 24 have their horizontal webs seated on the tops of the plates 20 and their ends abutting the sides 2 of the sections so as to brace the latter. The angle strips 24 are secured in position by bolts 25 and extend across the open outer ends of the seats 23 so as to close the latter, and by engaging the pipes hold the latter in position. The flanges of the plates 20 are held in position by means of bolts 26.

As shown in Fig. 6, the sections are embedded in the wall and with their flanges 4 flush with the face P of the plaster, the cover 5 being exposed.

From the foregoing, it will be apparent that in event of leakage, the cover plates may be removed without destroying the plaster. The invention is especially designed for large buildings wherein the walls are usually painted, in which instance the cover plates are also painted and can be easily and quickly removed as is apparent. The invention is susceptible of use with papered walls, but in the latter instance, the paper must be cut to enable access to the covers.

While I have shown nuts 6 in the drawing, still it will be obvious that these can be dispensed with if desired and the screws 7 directly threaded into the flanges 3.

What is claimed is:—

1. In a wall duct, a box formed to be vertically embedded in a wall, having a back, and sides, the latter being flanged outwardly to be parallel to the back and having their free edges extended outwardly to lie

at right angles to the flanges, nuts fixedly secured to the rear faces of the flanges, a cover seated on the flanges and engaged between the right angular free edges of the flanges, screws extending through the cover and flanges and threaded into the nuts, a transverse plate secured in the box and having U-shaped pipe seats therein opening through the front edge of the plate, an angular strip seated on the plate and extending across the seats to hold the pipes in the seats, and means to secure the strip in position.

2. In a wall duct, a box formed to be vertically embedded in a wall, having a back, and sides, the latter being flanged outwardly to be parallel to the back and having their free edges extended outwardly to lie at right angles to the flanges, nuts fixedly secured to the rear faces of the flanges, a cover seated on the flanges and engaged between the right angular free edges of the flanges, screws extending through the cover, and flanges and threaded into the nuts, and pipe holding means within the box.

3. In a wall duct, a box formed to be embedded in a wall and having an open front, a cover for the front, means to removably connect the cover to the box, a transverse plate secured in the box and having U-shaped pipe seats therein opening through the front edge of the plate, a strip engaged with the plate and extending across

the seats to hold the pipes in the latter, and means to secure the strip against movement.

4. In a wall duct, a box formed to be embedded in a wall and having an open front, a cover for the front, means to removably connect the cover to the box, a transverse plate secured in the box and having U-shaped pipe seats therein opening through the front edge of the plate, said plate having a flanged rear and ends engaged with the rear and sides respectively of the box, an angular strip having one side seated on the plate and extending across the seats to hold the pipes therein and engaged at its ends with the sides of the box, said strip having its other side depending from the plate, and means to secure the strip to the plate.

5. In a wall duct, a sectional conduit, each section having an open front, a back and sides each provided with a separate extension, the extensions of the back and sides of one section being offset to form tongues and the extensions of the back and sides of the adjacent section being bent downwardly and then upwardly to form sockets to receive the tongues, a cover for the open front, means to secure the cover in position, and pipe holding means in the sections.

In testimony whereof I affix my signature.

HENRY REZAC.
